[57] CLAIM

The ornamental design for a scraper-spoon, as shown and described.

DESCRIPTION

FIG. 1 is a perspective view of a scraper spoon showing my new design;

FIG. 2 is a top plan of the scraper-spoon;

FIG. 3 is a bottom plan thereof;

FIG. 4 is a left side elevation thereof, the right side elevation being a mirror image of the left side elevation;

FIG. 5 is a rear elevation thereof; and,

FIG. 6 is a front elevation thereof.

The broken line showing of a handle in FIGS. 1-4 and 6 is for illustrative purposes only and forms no part of the claimed design.
